UNITED STATES PATENT OFFICE.

RICHARD M. BECKER, OF BROOKLYN, NEW YORK, ASSIGNOR, BY MESNE ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,247,205.

Specification of Letters Patent. Patented Nov. 20, 1917.

Application filed October 28, 1913. Serial No. 797,733.

To all whom it may concern:

Be it known that I, RICHARD M. BECKER, a citizen of the United States, residing in Brooklyn borough, city of New York, in the county of Kings and State of New York, have invented certain new and useful Improvements in Combined Type-Writing and Computing Machines, of which the following is a specification.

10 My invention relates to combined computing and writing machines, and especially to devices adapted to prevent the types from striking the platen, as, for example, to prevent printing during computation. Certain 15 features may be used in typewriting machines to prevent printing whenever desired, as when the end of a line has been reached, etc.

A feature of the invention is the provision 20 of means for shifting the platen at any time into and out of the range of the types, for use in computing machines. The platen carriage and the guide rail with which it has a traveling connection in letter-feed direction 25 may have a shiftable connection with the machine frame, permitting the platen to be shifted toward and from the printing point. Blocks fixed to the machine frame may extend into slots formed in the guide rail, permitting 30 the guide rail, and with it the carriage, to be shifted in a forward and rearward direction. The shifting movement may be effected by means of a shift rod extending longitudinally through the guide 35 rail, which for that purpose is in the form of a tube or sleeve, said rod carrying pins working in cam slots in said blocks so that as the rod is moved longitudinally in the guide rail, the rod and sleeve are at the same 40 time cammed in a transverse direction to shift the platen.

The movement of the rod may be effected by a non-print key on a collar or ring journaled on the rod between the end of the 45 guide rail and the head on the rod, said collar and guide rail having cooperating cam faces to move the rod longitudinally when the key is actuated.

Other features and advantages will hereinafter appear.

In the accompanying drawings, which illustrate a form of the invention applied to an Underwood-Hanson combined typewriting and adding machine,

55 Figure 1 is a part sectional end elevation

view of a portion of the machine, the platen being shifted to non-printing position.

Fig. 2 is a fragmentary end elevation showing the non-print key shifted to normal position for printing.

Fig. 3 is a part sectional view showing the carriage guide rail and the shifting rod therein, the parts being in the position indicated by Fig. 1.

Fig. 4 is a similar view, but with the non-print key shifted to the Fig. 2 position.

Fig. 5 is a perspective view of the mechanism shown in Fig. 3.

Fig. 6 is a part sectional plan view showing the adjustable connection between the 70 guide rail and the machine frame.

The rotary platen 1 is mounted in a frame 2 on the carriage 3, the platen shaft having bearings in arms 4 pivoted at 5 to the carriage, so that the platen may be shifted to 75 upper and lower case positions. Type-bars 6 pivoted on a rod 7 in a type-bar segment 8, carry upper and lower case types 9 and 10, adapted to be brought to printing position at the front of the platen when the type-bars 80 are swung upward to the full line position in Fig. 1, the platen being normally in the dotted line position. The type-bars are actuated by keys 11 comprising levers 12 fulcrumed at 13 and connected by bell cranks 14 85 to the type-bars.

The numeral keys 11^a in the form of machine herein shown are provided with pendants 15 which strike bell cranks 15^a to set up on computing mechanism (not shown) the 90 numbers represented by the keys struck. If it is desired to set up numbers without printing on the platen, or for any other purpose to actuate the type-bars without permitting them to strike the platen, the latter is shifted 95 rearwardly to the full-line position, Fig. 1, out of range of the type-bars, which, when swung upward, strike a stop 16 on the segment 8. The stop 16 positively limits the movement of the types except for a slight 100 forward spring due to the resiliency of the type-bar, which, however, is insufficient to bridge the space between the types and platen.

The stationary guide rail 17 with which 105 the carriage 3 is slidably connected by means of bearing lugs 18, is, in accordance with the present invention, in the form of a sleeve or tube having an adjustable connection with blocks 19 which may be fixed in 110

the usual way to each end of the machine frame 20, and which form a support for the rail 17 and the carriage. These blocks may be extended forward through slots 21 in the front and rear walls of the tube 17, this connection permitting said tube to be adjusted forwardly and rearwardly at each end, but preventing either rotary movement or movement of the tube in the direction of the carriage travel, as the blocks 19 preferably have a close sliding fit in the tube. In order to shift the tube 17, and with it the carriage, a rod 22 extends through the tube and has a limited longitudinal movement therein, permitted by slots 23, through which the blocks 19 extend. Guide pins 24, fixed in the rod 22, extend through cam slots 25 in the blocks 19. When the rod 22 is shifted longitudinally in each end of the sleeve 17 (see Figs. 3 and 4) the pins 24 working in the slots 25 cam the sleeve 17 and with it the platen in a forward or rearward direction, the slots 25 being of such width as to prevent any movement of the sleeve 17 independently of the movement of the rod 22. The inclination of the slots 25 to the direction of the rod 22 is preferably insufficient to permit forward or rearward pressure on the guide rail 17 to produce a tension between the guide rail and rod in the direction of their length, so that the guide rail and carriage are positively held against forward or rearward movement.

The shifting rod 22 is shifted by means of a key 26 fixed to a collar 27 loose on the rod, and interposed between one end of the sleeve 17 and a head 28 on the end of the rod 22. The collar 27 comprises sections 29 and 30 of different widths, providing surfaces bearing against the end of the sleeve and connected by an inclined or cam surface 31, the end of the sleeve 17 being correspondingly shaped so that when the collar 27 is rotated by means of the key from the normal position at Fig. 4 to the Fig. 3 position, the rod 22 is cammed to the right, and each pin 24 being carried to the right along the slot 25 during such movement, forces the rod 22, and with it the sleeve 17, rearwardly, thus moving the platen away from the printing position.

A coil spring 32 mounted on the left-hand end of the rod 22, bears against the end of the sleeve 17 and a head 33 on the rod 22, so that when the platen is shifted rearwardly, the spring is placed under compression, and so acts automatically to return the parts to normal position when the key 26 is returned. It will be noted that when the platen is shifted to the rear, the sleeve 17 is positively held in shifted position by the collar 27, the wide section 29 thereof bearing squarely against the sleeve so there is no tendency of the spring 32 to accidentally return the sleeve. Also, the inclination of

the slots 25 is such that the forward or rearward pressure of the sleeve on the rod cannot shift the latter longitudinally of the sleeve. Thus the parts are rigidly held and positively locked in both printing and non-printing positions.

In assembling the parts, either head 28 or 33 of the rod 22 may be secured to the rod after the tube 17, collar 27 and spring 32 have been assembled on the rod. The pins 24 may be inserted in the rod through openings 24^a in the tube 17, said openings being afterward plugged, if desired.

Variations may be resorted to within the scope of the invention, and portions of the improvements may be used without others.

Having thus described my invention, I claim:

1. The combination of a carriage, a hollow guide rail along which the carriage travels in a longitudinal direction, said rail formed with slots, stationary supporting blocks extending into said slots, and a rod extending through said rail and having a cam connection with said blocks whereby said rail can be shifted laterally when the rod is operated.

2. The combination of a carriage, a hollow bearing sleeve on which the carriage is mounted to travel, a rod movable longitudinally in said sleeve, bearing blocks fixed to the machine frame and extending into slots formed in said sleeve and rod, a cam slot and pin connection between said rod and blocks, and means to shift said rod longitudinally in the sleeve.

3. In a writing machine, the combination of a machine frame, supporting blocks fixed thereto and extending in a forward direction, a bearing sleeve provided with slots into which said blocks extend, a rod extending through said sleeve and formed with slots through which said blocks extend, pins carried by said rod and extending through the slots therein, said blocks formed with inclined slots through which the pins extend, a key rotatable upon said rod, said key and sleeve having co-operating cam faces formed to shift the rod longitudinally when the key is rotated, and a carriage mounted to travel on said sleeve.

4. In a writing machine, the combination of a machine frame, supporting blocks fixed thereto and extending in a forward direction, a bearing sleeve provided with slots into which said blocks extend, a rod extending through said sleeve and formed with slots through which said blocks extend, pins carried by said rod and extending through the slots therein, said blocks formed with inclined slots through which the pins extend, a key rotatable upon said rod, said key and sleeve having co-operating cam faces formed to shift the rod longitudinally when the key is rotated, said sleeve and key

formed to positively lock said rod in shifted position, a spring to automatically return the rod when the key is returned, and a carriage having a traveling connection with the 5 sleeve.

5. In a typewriting machine, the combination with a carriage, of a rail on which it travels and by which it is held alined, a platen on said carriage, types arrested independently of said platen but printing thereon, a fixed member for so arresting said types, a support for said rail at each end thereof, and means coöoperating with each support for positively and separately moving both ends of said rail simultaneously to and from said fixed member.

6. A combined writing and computing machine comprising, in combination, a carriage, a platen thereon, types to strike the 20 platen, a guide rail on which the carriage is guided, stationary supporting blocks having a slidable connection with the rail, and means to slide said rail on the blocks and thereby shift the carriage and platen out of 25 striking range of the types.

7. In a typewriting machine having a frame and a traveling platen, the combination with type bars adapted to strike said platen to print thereon, of a fixed member 30 connected to said frame adapted to arrest said type bars to control the printing impression, said type bars being adapted to yield when striking said fixed member, a carriage carrying said platen, a rail on 35 which said carriage travels, means for supporting said rail at each end thereof, and a finger-piece adjustable to set said rail simultaneously at both ends and hold it positively at various distances relative to said fixed 40 member.

8. In a typewriting machine having a frame and a traveling platen, the combination with type bars adapted to strike said platen to print thereon, of a fixed member 45 connected to said frame adapted to arrest said type bars to control the printing impression, said type bars being adapted to yield when striking said fixed member, supports for separately holding each end of 50 said platen at an adjustable distance from said fixed member, and means for simultaneously adjusting said supports and positively holding said platen at the resultant distance from said fixed member.

55. 9. In a typewriting machine having a frame and a traveling platen, the combination with a fixed member forming part of said frame, of type bars comprising types for printing on said platen and adapted to strike said fixed member to determine how 60 they shall print, said type bars springing to effect such printing, a separate cam for sup-

porting each end of said platen to hold it at a predetermined relation to said fixed member, and means for simultaneously causing said cams to shift said platen to and from said fixed member. 65

10. A typewriting machine comprising, in combination, a carriage, a platen thereon, types to strike against the platen for printing, a guide rail along which the carriage has a letter-feed travel and by which the platen is held in coöperative relation to the types, and a key for shifting said guide rail in the direction in which the types approach 70 the platen, thereby carrying the platen out of operative relation to the types and preventing the types from printing. 75

11. In a typewriting machine having a frame and a traveling platen, the combination with a fixed member forming part of said frame, of type bars comprising types for printing on said platen and adapted to strike said fixed member to determine how they shall print, said type bars springing to 80 effect such printing, a separate cam for supporting each end of said platen to hold it at a predetermined relation to said fixed member, means for simultaneously causing said cams to shift said platen to and from 85 said fixed member, and connections whereby said cams hold said platen positively set in its adjusted position. 90

12. In a typewriting machine, the combination with a traveling platen and a frame, 95 of type bars comprising types for printing on said platen, a fixed member which said bars strike as they approach the platen to control the printing on the platen, two members supporting said platen, a cam device 100 associated with each member adapted to adjust said platen relatively to said fixed member, a single member for adjusting said devices, and cams associated with said last-named member for positively holding the 105 platen in its adjusted position.

13. In a typewriting machine having a frame and a traveling platen, the combination with type bars adapted to strike said platen to print thereon, of a fixed member 110 connected to said frame adapted to arrest said type bars to control the printing impression, said type bars being adapted to yield when striking said fixed member, means for adjusting said platen to and from said fixed 115 member, and a finger-piece for effecting said adjustment, said finger-piece adapted to serve as an indicator of the nature of said adjustment.
